UNITED STATES PATENT OFFICE.

PARDON A. WHITNEY, OF SOUTHBURY, CONNECTICUT, ASSIGNOR TO
THE PECK, STOW & WILCOX COMPANY, OF SAME PLACE.

DESIGN FOR A CLAMP-FRAME.

SPECIFICATION forming part of Design No. 18,376, dated June 5, 1868.

Application filed March 8, 1868. Serial No. 206,642. Term of patent 14 years.

To all whom it may concern:

Be it known that I, PARDON A. WHITNEY, a citizen of the United States, residing at Southbury, in the county of Hartford and State of Connecticut, have invented and produced a new and original Design for Clamp-Screw Frames, of which the following is a specification, reference being had to the accompanying drawings, forming part thereof.

Figure 1 is a side elevation of my newly-designed clamp-frame, and Fig. 2 is a transverse section thereof on line $x-x$ of Fig. 1.

The general contour of the frame is of the hooked or C shape ordinarily found in clamp-screw frames.

The leading features of my design consist of the beads at the edge of the body of the clamp-frame and the beads and band around the head.

A designates the body of my clamp-frame, and B designates the head. Along the inner edge of the body A, upon each side, is a bead,

a, and upon the outer edge are the beads b b and c. Around the head B of the clamp-frame are the beads d d, one at each end, said beads meeting the beads a and b at the junction of the head and body, as shown. There is a plain band, f, immediately inside the bead d, as shown. The space inclosed by the beads a and b on the body of the clamp-frame is provided with an ornamental groundwork--as, for instance, fine lines crossing each other.

I claim—

The design for a clamp-screw frame herein shown and described, the same consisting of the body A, having the beads a a along the inner edge and the beads b b and c upon the outer edge, and the head B, having beads d e at the upper and lower ends and the band f upon the inside of the lower band, d.

PARDON A. WHITNEY.
